GARMENT

Dorothy Rothstein, New York, N. Y.

Application November 5, 1938, Serial No. 238,985

3 Claims. (Cl. 2—71)

This invention relates to garments such as dresses, play suits or bathing suits for girls or women.

An object of this invention is to provide a garment of the character described which when worn will eliminate the necessity for wearing underwear, and which will nevertheless conceal the crotch portion of the body of the wearer, when the wearer sits, moves about, exercises or assumes almost any position, while permitting perfect freedom of movement.

Heretofore, play suits or bathing suits for girls or women have been made by combining a pair of pants or shorts with a skirt thereover to make the garment look feminine. In accordance with the present invention, the garment is not a modification of any pants or shorts, the pants or shorts being wholly eliminated, whereby the garment is wholly feminine in appearance.

20 The improved garment has a skirt with a diaphragm or bottom beneath, stitched to the skirt below the waistline, eliminating restriction of the legs and producing an attractive appearance.

In prior play suits or bathing suits for women, 25 the pants part of the garment had to be snug on the legs, otherwise, underwear had to be worn. With my garment although there is no constricting snugness, yet there is perfect concealment without necessity for underwear beneath the skirt. In previous play suits or bathing suits, 30 when the skirt part was lifted pants were revealed, which is not feminine looking. In my improved garment, if the skirt is lifted, the appearance is that the entire skirt is lined underneath 35 with only the legs coming through, and there is no pants exposed.

Another object of this invention is to provide a rugged and durable garment of the character described, which will fit a relatively large variety 40 of figures, which shall be relatively inexpensive to manufacture, attractive and wholly feminine in appearance, and yet practical and efficient to a high degree.

Other objects of this invention will in part be 45 obvious and in part hereinafter pointed out.

The invention accordingly consists in the features of construction, combinations of elements, and arrangement of parts which will be exemplified in the construction hereinafter described, 50 and of which the scope of application will be indicated in the following claims.

In the accompanying drawing, in which is shown one of the various possible illustrative embodiments of this invention,

55 Fig. 1 is a front elevational view of a garment,

embodimenting the invention, with parts broken away;

Fig. 2 is a cross-sectional view taken on line 2—2 of Fig. 1;

Fig. 3 is a bottom plan view of the garment 5 shown in Fig. 1, with the dress opened out into horizontal position;

Fig. 4 is a cross-sectional view taken on line 4—4 of Fig. 3;

Fig. 5 is a top plan view of a piece of cloth 10 from which the skirt is made; and

Fig. 6 is a plan view of a piece of cloth from which the skirt bottom is made.

Referring now in detail to the drawing, 10 designates a garment, embodying the invention. 15 The invention is here shown in the form of a dress or play suit for a little girl. The same comprises a waist portion 11 provided with sleeves 12, a skirt portion 13, and a combination skirt lining and bottom 14.

The skirt portion 13 is made from a flat circular piece of cloth 15 having a central opening 16. The piece of cloth 15 may be provided with a radial dart 17, extending outwardly from opening 16, for the purpose hereinafter appearing. The opening 16 forms the waistline for the skirt 13.

The skirt bottom 14 is made from a flat circular piece of cloth 18, of substantially the same diameter as the piece of cloth 15. The piece of cloth 18 is formed with two similar holes 19, 30 symmetrically disposed about a diametrical line passing through said piece of cloth and extending from front to rear (top to bottom in Fig. 6). The openings 19 eventually form leg openings through which the legs of the wearer pass.

Looking at Fig. 6 of the drawing, the bottom of the piece of cloth 18 will be at the rear of the dress, and the top will be at the front.

The openings 19 are closer to the front than to the rear, to allow more room at the rear than at the front. The openings 19 have straight inner edges 20, inclined toward the front, as shown in Fig. 6. Extending from the rear ends of the straight edges 20, are substantially semicircular edges 21 connected to the front ends of said 45 straight edges by inwardly curved edges 21a.

In making the dress, the piece of material 15 is placed on the piece of material 18 to register therewith, with the dart 17 on a diametrical line between the openings 19 and rearwardly of said 50 openings.

The pieces of cloth 15 and 18 are then stitched together by a circular line of stitching 22, adjacent the outer registering edges of said pieces of cloth. Said outer edges may be folded in- 55

wardly and stitched together by said line of stitching 22. The pieces of cloth 15 and 18 may then be stitched together by a plurality of circular, concentric lines of stitching 23. The innermost line of stitching 23 preferably has a radius about half the radius of the piece of cloth 15.

The openings 19 are located in the central portion 30 of the piece of cloth 18, within the innermost circular line of stitching 23. The diameter of the opening 16 is preferably less than the diameter of the portion 30 of the piece of material 18.

The waist portion 11 of the garment may be made in any suitable manner, and is stitched to the upper end of the skirt 13 by a line of stitching 32. The body 11 may be provided with slide actuated fasteners 33 at the rear. Said fasteners 33 may be attached to the edges of the dart or slit 17, so as to extend down below the top of the skirt 13.

It will now be noted that the portion 31 of the piece of cloth 18 between the smallest line of stitching 23 and the largest circular line of stitching 22, constitutes a lining for the skirt 13, and the portion 13 constitutes a diaphragm which contacts the legs of the wearer only at the rim edges of the openings 19. Any suitable decorative binding 35 may be attached to the edges of the openings 19.

It will now be understood that when the skirt is lifted, the body of the wearer above the openings 19 is entirely concealed, thus eliminating the necessity for separate pants or shorts.

It will be noted that no part of the garment hugs or constricts the legs or hips of the wearer, with the exception of the edges at the openings 19, thereby permitting freedom of body movement and permitting the garment to fit different figures.

Play suits or bathing suits have heretofore been made of a skirt portion and a pants portion. The present dress does not have a pants portion, but merely a diaphragm on the underside of the skirt provided with a pair of openings for the legs. The leg openings 19 being located closer to the front of the piece of material 18, provide additional material at the rear necessary for comfort to the wearer. Since the inner edges of the openings 19 diverge towards the rear, the garment gives the necessary comfort of movement while effectively concealing the crotch of the wearer.

If desired, the portion of piece of cloth 18 between the inner line of stitching 23 and the outer edge thereof, may be omitted.

Although the invention has been illustrated in the drawing in the form of a play suit or dress

for a little girl, it will be understood that the invention may be embodied in dresses, play suits or bathing suits for women as well as girls.

It will be also understood that the pieces of cloth 15 and 18 may be made of a number of 5 pieces of cloth stitched together or all in one piece, as shown in the drawing. Furthermore, the pieces of cloth 15 and 18 need not form complete circles, but may comprise segments of circles, it being preferable, however, that the bottom member comprise a piece of cloth which registers with the portion of the skirt above the top line of stitching 23.

It will thus be seen that there is provided a device in which the several objects of this invention are achieved, and which is well adapted to meet the conditions of practical use.

As various possible embodiments might be made of the above invention, and as various changes might be made in the embodiment above set forth, it is to be understood that all matter herein set forth or shown in the accompanying drawing is to be interpreted as illustrative and not in a limiting sense.

Having thus described my invention, I claim 25 as new and desire to secure by Letters Patent:

1. A play suit having a skirt portion made of a flat circular piece of cloth, having a central opening forming the waistline of the skirt portion, and a combination lining and bottom for said skirt made of a flat circular piece of cloth of substantially the same diameter as the diameter of the skirt portion, stitched to the underside of said skirt portion by a plurality of concentric circular lines of stitching, the central portion of 30 said second circular piece of cloth being unstitched to the skirt and provided with a pair of openings symmetrically disposed about a diametric line, to receive the legs of the wearer.

2. In a garment, a skirt, and a flat substantially circular piece of cloth attached to the underside of the skirt on a circular line nearer to the waistband than the lower edge of the skirt and having a pair of leg openings formed therein.

3. In a garment, a skirt made of a flat circular 45 piece of cloth, having a central opening forming the waistline of the skirt, and a combination lining and diaphragm for said skirt made of a flat circular piece of cloth substantially the same size as the piece of cloth from which the skirt is 50 made, said lining being stitched to the underside of the skirt at its lower edge portion and also at its intermediate portion at a point nearer to the waistline than the lower edge of the skirt, said diaphragm portion having its central portion 55 unattached to the skirt and provided with a pair of leg openings.

DOROTHY ROTHSTEIN.
